UNITED STATES PATENT OFFICE.

RALPH ABRAHAM SCHOENBERG, OF NEW YORK, N. Y.

LOCK FOR SOCKET-SHELLS.

1,172,635.

Specification of Letters Patent. Patented Feb. 22, 1916.

Application filed December 26, 1914. Serial No. 878,988.

To all whom it may concern:

Be it known that I, RALPH A. SCHOENBERG, of New York, in the county of New York and State of New York, have invented 5 a new and useful Lock for Socket-Shells, of which the following is a specification.

The main object of my invention is to increase the durability and efficiency of socket shells, whether key or keyless, and particularly with regard to the bayonet lock of such 10 sockets, an example of the prior art appearing in U. S. Letters Patent to W. H. Perkins No. 781,226 dated January 31, 1905.

It is the well-nigh universal custom in 15 removing the cap from the body of a bayonet-jointed socket shell, such, for example, as appears in said patent to tip the cap as if it were hinged instead of pulling the cap straight off longitudinally. The result is 20 that the screw-head of the screw at the rear (as the shell is held in the hand) presses against the flange of the cap and also forces the lower edge of the flange against the body in such a way as to seriously bend and dis- 25 figure the parts and also to bend or tear off the head of the screw. This is due to the tipping of the cap in removing it, which tipping is practically universal and results in such disarrangement and bending that the 30 parts of the lock become relatively loose or will not lock at all.

A feature of my invention overcomes these 35 defects and consists in dispensing with the screw and with the attendant necessity of threading of the body portion and providing a stud or pin without a head to prevent relative longitudinal movement between the cap member and body member of the socket shell when those parts are locked together.

Another feature of my invention consists 40 in providing a round edge for a portion of the bayonet slot to prevent cutting into the boss which engages said portion.

Another feature is a boss sloping out- 45 wardly in the direction of the crosswise por- tion of the bayonet slot to provide for easy riding of the flange of the cap up on to said boss.

Another feature consists in an internal 50 projection on one or more of the studs to engage an insulating member within the shell and prevent rotation thereof.

Another feature consists in the fastening 55 of the studs in place.

Other features will be pointed out below.

In the drawings: Figure 1 is an elevation of a keyless socket shell embodying my invention; Fig. 2 is a perspective of the cap member; Fig. 3 is an elevation of the body member; Fig. 4 is a section on line 4—4 of 60 Fig. 3; Fig. 5 is an enlarged section on line 5—5 of Fig. 1; Fig. 6 illustrates one form of boss; Fig. 7 is an elevation of the body member adapted for use with a key; Fig. 8 is a section; and Fig. 9 is a broken elevation of 65 another form of cap flange.

In Fig. 1 the socket shell is of the keyless form and includes cap A and body B having a bayonet joint connection the cap having a slot with a portion extending longitudinally 70 of the device and another portion a extending sidewise of the longitudinal portion. Body B has a projection or boss b made by a portion being pressed out as indicated in Figs. 1 and 5. The body B is slit at b' to enable said body to be pressed inwardly in the neighborhood of said projection. Body B is also provided with a stud or pin b^2 which is made without a head and which has a pressed-out shoulder b^3 to engage the out- 75 side of a bent-in portion b^4 of the body B, the inner portion b^5 being riveted in place. In Fig. 4 I show one stud having an internal projection b^6 to enter recess b^7 and thereby prevent rotation of insulating member 80 b^8 . The lower portion of the left edge of the bayonet slot is rounded being formed by cutting the flange a' at a^2 and bending back that portion of the flange which ex- 85 tended from a^2 to a^3 so as to form a flap a^4 having the rounded edge a^5 . This flap could be bent inwardly instead of outwardly as both forms would have the rounded edge which is highly desirable for the reason that if the edge is made flat as heretofore 90 it cuts the boss on the body after a time and so renders the device inefficient because said edge works under the boss making disen- 95 gagement of the parts difficult.

In Fig. 6 I show a boss B' which is round- 100 ed in order to provide an outward slope in a direction parallel to the sidewise exten- sion a so as to facilitate the passing of flange a' over said boss when the parts are to be disengaged.

In Fig. 7 I show the body member with a slot B^2 to receive a key.

In Figs. 8 and 9 instead of cutting away the portion of material extending from a^2 to a^3 in Fig. 2 I press out said material at 110

D which permits the passage of boss d but makes the cap flange d' stronger than if the material were cut away.

I have used the expression "boss" or "projection" and it is to be understood that this expression includes any projection, such for example, as a rivet.

What I claim is:

1. A device of the character described comprising a cap with a bayonet slot and having a portion bent back upon itself to form a rounded edge for a portion of said slot; and a body having a boss to engage said edge to prevent relative rotation of the cap and body in one direction.
2. A device of the character described comprising an insulating member; a cap with a bayonet slot; a body having a boss to engage said slot to prevent relative rotation of the cap and body in one direction and having a stud to engage said slot to prevent relative longitudinal movement of the in the opposite direction and also to prevent relative longitudinal movement of the cap and body, said stud having internal extending means coöperating with said insulating member to prevent rotation of the latter.
3. A device of the character described comprising an insulating member with a recess; a cap with a bayonet slot; a body having a boss to engage said slot to prevent relative rotation of the cap and body in one direction and having a stud to engage said slot to prevent relative rotation of the cap and body in the opposite direction and also to prevent relative longitudinal movement

of the cap and body, said stud having an internal extension to enter said recess and thereby prevent rotation of the insulating member.

4. A device of the character described comprising a cap with a bayonet slot; and a body having a headless stud riveted thereto to engage said slot to prevent relative longitudinal movement of the cap and body in the locked position.

5. A device of the character described comprising an insulating member; a cap with a bayonet slot; a body having means to coöperate with said slot to lock the cap and body together, said means having a member to engage said insulating member to prevent rotation thereof.

6. A device of the character described comprising an insulating member; a cap with a bayonet slot; a body having a stud to engage said slot to prevent relative longitudinal movement of the cap and body, said stud having an internal projection to engage said insulating member to prevent rotation thereof.

7. A device of the character described comprising a cap member and a body member having a bayonet joint connection, one of said members having a bayonet slot with an edge rounded about an axis substantially parallel to the longitudinal axis of the device and the other of said members having a boss to engage said edge.

RALPH ABRAHAM SCHOENBERG.
